US0D1004457S

(12) **United States Design Patent** (10) **Patent No.:** **US D1,004,457 S**
(45) **Date of Patent:** **** Nov. 14, 2023**

(54) **DOORBELL**

(71) Applicant: **Amazon Technologies, Inc.**, Seattle, WA (US)

(72) Inventors: **Matthew J. England**, Santa Monica, CA (US); **Mark D. Siminoff**, Mountain View, CA (US); **Wen-Yo Lu**, Pasadena, CA (US); **Christopher Loew**, Palo Alto, CA (US); **James Siminoff**, Pacific Palisades, CA (US); **Spiro Sacre**, Los Angeles, CA (US)

(73) Assignee: **Amazon Technologies, Inc.**, Seattle, WA (US)

(**) Term: **15 Years**

(21) Appl. No.: **29/869,113**

(22) Filed: **Dec. 21, 2022**

Related U.S. Application Data

(62) Division of application No. 29/826,004, filed on Feb. 8, 2022, now Pat. No. Des. 976,734, which is a division of application No. 29/726,509, filed on Mar. 3, 2020, now Pat. No. Des. 945,898.

(57) **CLAIM**

The ornamental design for a doorbell, as shown and described.

DESCRIPTION

FIG. 1 is a top, front, right-side perspective view of a doorbell;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The dashed broken lines depict portions of the doorbell that form no part of the claimed design.

1 Claim, 8 Drawing Sheets
